UNITED STATES PATENT OFFICE

SAMUEL A. STRANAHAN, OF FLINT, MICHIGAN, ASSIGNOR TO GENERAL MOTORS CORPORATION, OF DETROIT, MICHIGAN, A CORPORATION OF DELAWARE

MUFFLER

Application filed January 24, 1927. Serial No. 163,155.

My invention relates to an improved muffler of the type commonly used in the exhaust pipe of internal combustion engines and has for its principal object the provision of a muffler which is so designed that the maximum silencing effect will be obtained with very little back pressure.

Another object is to so construct a muffler that it will not only reduce the sound of the explosion but at the same time will be free from the ringing, metallic sound so often present in the usual mufflers.

Other objects and advantages will be apparent upon referring to the specification and accompanying drawing, in which:

Fig. 1 is a longitudinal sectional view through the center of my improved muffler.

Fig. 2 is a section taken on line 2—2 of Fig. 1;

Fig. 3 is a section taken on line 3—3 of Fig. 1.

The numeral 10 indicates a casing having end plates 12 and 14 preferably welded in place to provide an air tight compartment.

The front plate 12 is formed with a flange 16 to receive the exhaust pipe leading from the engine. The rear plate 14 also has a flange 18 to which is attached a pipe leading to the rear of the vehicle where the exhaust gases

are discharged into the atmosphere. In addition this plate is constructed with a conical shaped portion 20 for a purpose to be described later. Within the casing there are five concave-convex discs held in place by being spot welded to the casing. These discs have different numbers of perforations in them to permit the proper expansion of the exhaust gases. For example in the particular embodiment illustrated, disc 22 has ninety

small perforations and disc 24 has eighty-two perforations of the same diameter. Disc 26 has one large opening and the next disc 28 has seventy perforations of substantially the same size as those in discs 22 and 24. The

last disc 30 has an opening of substantially the same diameter as that in disc 26 and is provided with a tapered tube 32 the large end of which is preferably spot welded to the disc concentric with the opening in the latter, the small end being spaced a short dis-

tance away from the rear plate 14 at a point substantially at the small end of the conical shaped portion 20.

In operation the exhaust gases enter the muffler through opening 34 and are free to expand to a certain extent in the chamber 36 after which they pass through the perforations in disc 22 into the chamber 38 where they may expand more. They next pass through the perforations in disc 24 into chamber 40, then through the large opening in disc 26 into chamber 42, then through the perforations in disc 28 into another chamber 44 after which they flow through the tapered tube 32 and out through the opening 46 to the atmosphere.

Due to the fact that there is a constant high velocity flow of gases through the tapered tube 32, it is obvious that there will be a partial vacuum in chamber 48 because of the Venturi effect caused by the arrangement of tube 32 within the conical shaped portion 20 of plate 14. The purpose of this vacuum chamber is to eliminate the ringing or metallic noise usually present in pressed steel mufflers. It also serves to give the sound of the escaping gases a very low pitch which is scarcely audible.

It is thought from the foregoing taken in connection with the accompanying drawing that the construction and operation of the device will be apparent to those skilled in the art, and that various changes in size, shape, and proportion and details of construction may be made without departing from the spirit and scope of the appended claims.

I claim:

1. A muffler comprising a casing, means in said casing for breaking up the stream of exhaust gases into a plurality of smaller streams, means for concentrating them into a single stream, a tube for discharging said single stream, and a vacuum chamber surrounding said tube for the purpose of reducing the sound of the discharge.

2. A muffler comprising a casing, spaced means in the casing for dividing the stream of exhaust gases into several smaller streams, the space between said means serving as an expansion chamber, means for concentrating

the smaller streams into a single stream, a tube carried by said second means from which said single stream is discharged, and a vacuum chamber surrounding said tube for the purpose of reducing the sound of the discharge.

3. A muffler comprising a casing, a series of discs containing different numbers of perforations held in the casing, and a tube carried by one of said discs through which the exhaust gases are discharged, and a vacuum chamber surrounding said tube for the purpose of reducing the sound of the discharge.

4. A muffler comprising a cylindrical casing having end plates, one of said end plates being formed with a conical shaped portion, perforated discs secured in the casing, and a tube carried by one of said discs, the rear end of the tube lying within the conical shaped portion, the spaces between the various discs forming expansion chambers and the space between one of said end plates and the adjacent disc forming a vacuum chamber.

5. A muffler comprising a cylindrical casing, front and rear end plates held in the casing, central openings in the end plates, a plurality of discs containing different numbers of small perforations, an intermediate disc having a relatively larger opening, an end disc having a large central opening, and a tube secured to the end disc concentric with the opening therein, the opposite end of the tube lying within the opening in the rear end plate, the space between the end disc and the rear end plate constituting a vacuum chamber.

6. A muffler comprising a casing having an inlet and an outlet, a cross-wall for said casing having a plurality of relatively small apertures therethrough, a second cross-wall in said casing between the first cross-wall and the outlet and being imperforate except for a single relatively large aperture and a tubular conduit surrounding said relatively large aperture and projecting toward said outlet and cooperating with said second cross-wall to provide a dead space surrounding the conduit, the parts being constructed and arranged to reduce pressure in the space surrounding said conduit.

In testimony whereof I affix my signature.
SAMUEL A. STRANAHAN.
